CIGARETTE PACKING MACHINE

George Daniel Morgan, Deptford, London,
EnglandApplication October 29, 1932, Serial No. 640,307,
and in Great Britain November 20, 1931

8 Claims. (Cl. 226—5)

This invention is for improvements in or relating to cigarette packing machines, and refers more particularly to apparatus for feeding pictures or card strips on such machines, and has for its object the provision of improved means whereby pictures or cards may be inserted between two superimposed rows of cigarettes.

It is found that when the cigarette picture or card strip is placed in this position, the packet containing the cigarettes, which is often a thin paper packet, is considerably reinforced.

The present invention consists of apparatus for use on a cigarette packing machine whereby a batch of cigarettes comprising two or more superimposed rows of cigarettes compacted ready for packing and which may be carried along by a conveyor or the like, is separated and a picture or card placed between the rows, after which the rows are brought together again with the picture between them.

The invention will be more particularly described with reference to the accompanying drawing, in which:—

Fig. 1 shows a section of a portion of a packing machine with the invention applied thereto.

Fig. 2 is a plan of Fig. 1.

Fig. 3 is a central section of Fig. 2, but with the parts in a slightly different position.

Fig. 4 is a similar view to Fig. 3, but to a larger scale and with the parts in a different position.

Fig. 5 is a similar view to Fig. 4, but showing the parts after the picture has been completely covered by the upper row of cigarettes.

Fig. 6 is a perspective view of a pusher piece.

Referring to the drawing which shows one way of carrying the invention into effect, the packing machine, the bed 1 of which is shown, is provided with a cigarette feeding apparatus of any suitable kind (not shown), and a pusher 2 mounted on a conveyor 3 is arranged to convey a batch 4 of cigarettes comprising at least two rows, from the cigarette feeding apparatus to the packing mechanism. The cigarettes are then carried along the bed 1 of the machine through a channel formed by guides 5 to the packing mechanism.

Any suitable type of picture feeding apparatus is mounted on the side of the machine and arranged to feed a picture down between conveyor bands 6 into the guide channel. Two thin plates 7 are mounted in the guide channel parallel to the bed and a sufficient distance above the same to permit a single row of cigarettes to pass beneath them, as shown in Fig. 3. The plates are cut away at the ends with which the cigarettes first contact, so that the distance between their op-

posite edges is about equal to the width of the guide channel and the edges gradually sweep inwards until they are fairly close together at the centre of the bed of the machine as shown in Fig. 2. In addition to this, the edges are bevelled as indicated by the shading at 8 so that they present a comparatively sharp edge to the oncoming cigarettes, and the pusher pieces 2 of the conveyor 3 are made with horizontal slots 9 at each side, leaving a narrow central rib 10 so that they can pass by the plates 7. The plates extend for a distance roughly equal to the length of the picture after they have approached close to one another as above mentioned, and the upper surfaces of the extended portions are cut away at 11 to form a recess in which a picture 12 can lie. The pictures are delivered one at a time by the belts 6 from the feeding apparatus on to the recessed surfaces 11 of the plates 7 so that they lie parallel to the guides in the lengthwise direction.

As each batch of cigarettes is carried along by the pusher piece, the sharp edges of the plates enter the space between the rounded portions of the two outer cigarettes, and this movement continues towards the middle of the rows until the top layer of cigarettes is separated from the bottom layer without injury to the cigarettes, and passes over the picture lying in the recess. As the pusher piece passes through the plates, the picture is gathered up by the central rib 10 of the pusher piece and carried off between the two layers of cigarettes, so that when the batch of cigarettes is clear of the two plates mentioned, the cigarette picture lies between the two rows forming the batch.

What I claim as my invention and desire to secure by Letters Patent is:—

1. In apparatus for inserting a flat blank between engaging rows of a batch of cigarettes, the combination with means for effecting separation of at least one row from the remainder of the batch to form the batch into two portions, of means for introducing a blank between the portions of the batch thus separated, and means for reassembling the separated portions of the batch with the blank between and contacting with cigarettes in each portion.

2. In apparatus for inserting a flat blank between two superimposed rows of a batch of cigarettes, the combination with means for feeding the batch with the rows in engagement through a predetermined path, of means extending into the path of movement of the batch for effecting separation of at least one row from the remainder.

- of the batch to arrange the cigarettes in two portions, and means for interposing a blank between the two portions. 6. In apparatus for inserting a flat blank between two superimposed rows of a batch of cigarettes, the combination with means for feeding the batch with the rows in engagement through a predetermined path, of means extending into the path of movement of the batch for effecting separation of at least one row from the remainder of the batch to arrange the cigarettes in two portions, said means comprising a pair of spaced stationary plates positioned so as to pass between the rows of the moving batch, means for depositing a blank on the plates, and means for removing the blank and the cigarettes from the plates after one portion of the batch has passed over the blank to reassemble the batch with the blank interposed between the rows. 80
3. In apparatus for inserting a flat blank between two superimposed rows of a batch of cigarettes, the combination with means for feeding the batch with the rows in engagement through a predetermined path, of means extending into the path of movement of the batch for effecting separation of at least one row from the remainder of the batch to arrange the cigarettes in two portions, said means comprising a stationary device positioned so as to pass between the rows of the moving batch, and means for interposing a blank between the two portions. 85
4. In apparatus for inserting a flat blank between two superimposed rows of a batch of cigarettes, the combination with means for feeding the batch with the rows in engagement through a predetermined path, of means extending into the path of movement of the batch for effecting separation of at least one row from the remainder of the batch to arrange the cigarettes in two portions, said means comprising a pair of spaced stationary plates positioned so as to pass between the rows of the moving batch, and means for interposing a blank between the two portions. 90
5. In apparatus for inserting a flat blank between two superimposed rows of a batch of cigarettes, the combination with means for feeding the batch with the rows in engagement through a predetermined path, of means extending into the path of movement of the batch for effecting separation of at least one row from the remainder of the batch to arrange the cigarettes in two portions, said means comprising a pair of spaced stationary plates positioned so as to pass between the rows of the moving batch, each plate having the leading edge thereof inclined in the direction of movement of the batch from the sides of the batch towards the central portion thereof, and means for interposing a blank between the two portions. 95

7. In apparatus for inserting a flat blank between two superimposed rows of a batch of cigarettes, the combination with a continuous conveyor for feeding the batch through a predetermined path, of means extending within the said path for lifting at least one row of cigarettes to effect separation of the batch into two portions, means for feeding a blank in position on said first named means, and means forming part of said conveyor for withdrawing the blank with the cigarettes from said first named means. 100
8. In apparatus for inserting a flat blank between two superimposed rows of a batch of cigarettes, the combination with a continuous conveyor for feeding the batch through a predetermined path, of a pair of spaced stationary elements extending into the path of movement of the batch to effect separation thereof, means for feeding a blank in position on said elements, and means carried by said conveyor and passing between said elements for withdrawing the blank with the cigarettes from said elements to effect reassembly of the batch with the blank interposed between the rows of cigarettes. 105
